UNITED STATES PATENT OFFICE.

CHARLES H. WOLFF, OF PHILADELPHIA, PENNSYLVANIA.

BASE-BALL GAME-BOARD.

No. 845,838.

Specification of Letters Patent.

Patented March 5, 1907.

Application filed June 1, 1904. Serial No. 210,646.

To all whom it may concern:

Be it known that I, CHARLES H. WOLFF, a citizen of the United States, residing at Philadelphia, in the county of Philadelphia and State of Pennsylvania, have invented 5 certain new and useful Improvements in Base-Ball Game-Boards; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

My invention relates to game-boards, and particularly to a game-board for playing the game of base-ball.

It has for its object to provide a game-board representing the diamond and field and figures of players positioned in the places ordinarily occupied by the members of a nine playing a game of base-ball, there being formed at the position of each player, 20 preferably at or adjacent to the hand or hands of each player, a cavity designed to receive and hold loosely a ball, which balls it is the purpose of the game to dislodge by means of an extra ball, which will be made 25 larger or colored differently from the other balls to distinguish it from them, and then to endeavor to reinstate in its place the dislodged ball or balls by manipulation of the game-board in the hands of the user or 30 player.

To the accomplishment of the foregoing and such other objects as may hereinafter appear the invention consists in the features of construction and arrangement of parts 35 hereinafter particularly described and then sought to be clearly defined by the claim, reference being had to the accompanying drawing, which represents a perspective view of a game-board made in accordance with my invention.

In the drawing the numeral 1 designates the base of the board inclosed by the raised walls 2, and which may be provided at each corner with a block 3 to sustain a glass plate 40 which will lie over the base, and which plate may be held in place by lips 4, which will extend inwardly from the walls 2. The base and walls and the lips may be made of metal or stiff paper or other suitable material. On 45 the face of the base 1 will be inscribed a diamond, (represented by the numerals 5 and 6,) the lines of the diamond being preferably

brown in color and with the lines leading from the home plate to the first base and from the third base to the home plate narrower or wider than the lines leading from the first base to the second base and from the latter to the third base, for the purpose of more quickly determining the several bases and positions of the players composing the 55 nine, and for effect the base of the board other than the lines indicating the run from one base to another and to home will be designated by a green color. The figures of the several players are designated by the numerals 7, and they will be positioned substantially as illustrated, so as to occupy their proper places as usual in playing a game of base-ball. At or adjacent to the hand or hands of each player on the base- 70 board will be formed a cavity or depression 8, in each of which cavities or depressions will be placed a ball 9, while at the position of the catcher or at some other suitable point will be formed a depression or cavity 10, in which 75 will be placed a ball 11, which, to distinguish it from the other balls, is illustrated as being somewhat larger than the other balls, although this ball may be distinguished from the others by being of a different color or 80 otherwise distinguished.

With the balls in the several cavities the board will be manipulated so as to direct the ball 11 against the other balls in succession, with the view of displacing said balls one 90 after the other and to prevent the displaced balls being replaced in the cavities until all of the balls have been displaced by contact therewith of the large ball 11. After the balls have been displaced then the game- 95 board will be manipulated so as to replace the balls in the cavities from which they were displaced. The game will thus afford a source of amusement and entertainment to adults as well as children, and by practice a 100 person may acquire such skill in the manipulation of the board as to be able to displace the several balls in proper succession or in such order as he may determine. If the game be played by two persons, for illustration, the first person manipulating the board will do so until he fails to dislodge one of the balls by contact of the large ball therewith, and upon his failure to dislodge a ball the other person will manipulate the board, and 105 so on in alternation, the person first dislodging the greater number of balls winning the 110

game. Any other rule, however, may be formulated between the persons playing the game for determining what shall constitute the winning of the game.

5 For convenience of designation I shall designate the ball 11 as the "propelling-ball" and the other balls as the "positioned balls."

10 While the illustration of the game-board given contemplates a size such as can be readily manipulated by the hands, still it can be made on a large scale and a cue of suitable form employed for moving the propelling-ball. In such case the glass covering for the board used on the small sizes would 15 be left off or omitted. The same rules for playing the game would prevail.

Having described my invention and set forth its merits, what I claim is—

A game-board comprising a base-board provided with figures of individuals positioned as in a game of base-ball, and a cavity or depression adjacent to the hand of each of the several individual figures, a series of balls to fit in said cavities, and a propelling-ball to dislodge the positioned balls from their cavities, substantially as described. 20 25

In testimony whereof I affix my signature in presence of two witnesses.

CHARLES H. WOLFF.
